CABINET INCLUDING COMPARTMENT HAVING SNAP-IN CLOSURE MEMBER

Raymond H. Herbert, Little Falls, N.Y., assignor to General Electric Company, a corporation of New York
Filed Dec. 27, 1966, Ser. No. 604,777
7 Claims. (Cl. 220—60)

ABSTRACT OF THE DISCLOSURE

A cabinet having a compartment including a generally L-shaped closure member, the closure member including integral positioning tabs and an integral deflectable spring finger adapted to be received by corresponding apertures in the cabinet to lock the closure member to the cabinet.

Background of invention

It is often necessary in consumer electronic equipment to provide compartments and associated closure members for the storage of various components and similar functions. For example, in portable tape recorder devices, it is desirable to provide a cabinet having such a closed compartment for storage of a microphone when the microphone is not in use.

In the past, various complicated and expensive arrangements have been utilized to provide such a compartment. For example, compartments have been employed utilizing closure members having discrete hinge and latch elements to attach the closure member to the cabinet. Such arrangements are unduly complicated and expensive and are subject to breakage.

Summary of the invention

It is an object of the invention to provide a simplified compartment and closure member arrangement for consumer electronic devices.

It is another object of the invention to provide a compartment and closure member arrangement that is less expensive than prior art devices.

It is a further object of the invention to provide a compartment and closure member arrangement that is less subject to breakage than prior art devices.

These and other objects are achieved in one embodiment of the invention by the provision of a cabinet including a storage compartment extending upwardly from the bottom surface of the cabinet and inwardly from the side surface of the cabinet. The compartment thus comprises a cavity having an open end and an open side.

A generally L-shaped closure member is provided including a pair of projecting positioning tabs and a deflectable spring finger adapted to be received by a corresponding aperture in the compartment. The compartment cover is so formed that it snaps into place, the inherent spring action between the two legs of the closure member maintaining the spring finger in the latched position.

Description of the drawings

The novel and distinctive features of the invention are set forth in the appended claims, the invention itself together with further objects and advantages thereof, may best be understood by reference to the accompanying drawings in which:

FIGURE 1 is a perspective view of a cabinet employing the compartment and closure member arrangement of the invention;

FIGURE 2 is an exploded partial perspective view of the compartment and closure member arrangement shown in FIGURE 1;

FIGURE 3 is a partial side view of the compartment shown in FIGURE 1 with the closure member removed;

2

FIGURE 4 is a partial sectional view taken along the lines 4—4 of FIGURE 3 with the closure member in a partially opened position; and

FIGURE 5 is a partial sectional view taken along the line 4—4 of FIGURE 3 with the closure member in the closed position.

Description of the preferred embodiment

Referring to FIGURE 1 there is shown generally at 1 a plastic cabinet for consumer electronic equipment such as a portable tape recorder. The cabinet 1 includes a pair of supporting feet 3 and 5 and a storage compartment shown generally at 7.

The storage compartment and associated closure member in accordance with the invention are shown most clearly in FIGURES 2 and 3. As depicted, the storage compartment comprises a cavity extending upwardly from the bottom surface 9 of the cabinet 1 and inwardly from the side surface 11 of the cabinet 1, the bottom surface 9 and side surface 11 being generally orthogonally related as shown. The compartment comprises a side wall portion 13, a pair of end wall portions 15 and 17, and a top wall portion 19 provided with a ledge 21.

A pair of closure member positioning slots 23 and 25 are provided in the top wall 19, a closure member latching aperture 27 being provided in the side wall 13.

In accordance with the invention, an L-shaped closure member is employed as shown generally at 29. Closure member 29 comprises a first leg portion 31 and a second leg portion 33 generally orthogonal thereto. The first leg portion 31 is provided on the inner surface thereof with a pair of upwardly extending positioning tabs 35 and 37.

The second leg portion 33 is provided with an inwardly extending deflectable spring finger 39 having a projection defining a transverse latching portion 41 positioned at the end thereof. The transverse latching portion 41 is adapted to be received by the latching aperture 27, the latching portion 41 being tapered at 43 to facilitate entry into the aperture 27 as shown.

As depicted, the supporting foot 3 shown in FIGURE 1 is formed integrally with the second leg portion 33, a portion 3' of the supporting foot being provided on the bottom surface of the cabinet 1.

Referring to FIGURE 4, the closure member 29 is shown with the positioning tabs 35 and 37 received by the corresponding slots 23 and 25 respectively. In this position, the closure member 29 may be pivoted as indicated by the arrow 45 to the closed position shown in FIGURE 5.

As depicted in FIGURE 5, the transverse latching portion 41 of the spring finger 39 is received by the latching aperture 27, the tapered portion 43 facilitating insertion of the transverse latching portion in the aperture. The closure member is so dimensioned that with the latching portion 41 received by the aperture 27 as shown in FIGURE 5, the spring finger 39 is deflected slightly upwardly from its rest position thereby exerting a downward force as indicated by the arrow 46 on the latching portion 41.

Thus, the transverse latching portion 41 engages the side wall 13 to retain the closure member 29 in the latched condition. It is seen that in this position, the inner surface of the first leg portion 31 is flush with the side surface 11 of the cabinet. Similarly, the second leg portion 33 is positioned flush with the bottom surface 9 of the cabinet 1 with the supporting foot 3 in registry with the foot portion 3'.

Thus, in accordance with the invention a snap-in closure member is provided wherein latching is provided due to the natural spring action of the closure member itself.

In order to remove the closure member to gain access to the storage compartment, an upward force is exerted on the second leg portion 33 and thus spring finger 39 to remove the transverse latching portion 41 from the aperture 27.

Although the invention has been described with respect to certain specific embodiments, it will be appreciated that modifications and changes may be made by those skilled in the art without departing from the true spirit and scope of the invention. Therefore, it is intended by the appended claims to cover all such modifications and changes that fall within the true spirit of the invention.

What is claimed and desired to be secured by Letters Patent of the United States is:

1. In a cabinet including first and second adjacent generally orthogonally related wall portions, a compartment arrangement comprising;
  - (A) A compartment extending inwardly from the first and second wall portions;
  - (B) A generally L-shaped closure member for the compartment comprising first and second generally orthogonally related leg portions;
  - (C) Said first leg portion including a positioning tab extending therefrom;
  - (D) Said second leg portion including a deflectable spring finger extending therefrom;
  - (E) Said spring finger being provided with a transversely extending latching portion at the end thereof;
  - (F) Said cabinet including a positioning slot adapted to receive said positioning tab and a latching aperture adapted to receive the latching portion of said spring finger, and
  - (G) The closure member being so dimensioned that said spring finger must be deflected from its rest position to be received by said latching aperture when said positioning tab is received by said position-

ing slot whereby said latching portion lockedly engages the cabinet.

2. The compartment arrangement defined in claim 1 wherein said compartment comprises a top wall portion, a side wall portion and first and second end wall portions.

3. The compartment arrangement defined in claim 2 wherein said first leg portion includes a plurality of spaced positioning tabs extending therefrom and said top wall portion of said compartment includes a plurality of corresponding slots adapted to receive said positioning tabs.

4. The compartment arrangement defined in claim 2 wherein said side wall portion of said compartment includes said latching aperture, said transverse latching portion engaging the inner surface of said side wall portion when said closure member is in the closed position.

5. The compartment arrangement defined in claim 2 wherein said top wall portion includes a ledge portion, said first leg portion of said closure member abutting said ledge portion to position said first leg portion flush with the first wall portion of said cabinet in the closed position.

6. The compartment arrangement defined in claim 1 wherein the first and second wall portions of the cabinet are side and bottom wall portions of the cabinet respectively and said second leg portion of said closure member is provided with a downwardly extending supporting foot.

7. The compartment arrangement defined in claim 1 wherein said transverse latching member is tapered to facilitate entry into said second aperture.

UNITED STATES PATENT OFFICE
CERTIFICATE OF CORRECTION

Patent No. 3,390,806

July 2, 1968

Raymond H. Hebert

It is certified that error appears in the above identified patent and that said Letters Patent are hereby corrected as shown below:

In the heading to the drawing, line 1, "R.H. HERBERT" should read -- R. H. HEBERT --; in the bottom right-hand corner, "RAYMOND H. HERERT" should read -- RAYMOND H. HEBERT --. In the heading to the printed specification, line 4, "Raymond H. Herbert" should read -- Raymond H. Hebert --.

Signed and sealed this 9th day of December 1969.
